US00D800106S

(12) **United States Design Patent** (10) **Patent No.:** **US D800,106 S**
Godycki et al. (45) **Date of Patent:** **** Oct. 17, 2017**

(54) **MOBILE COMMUNICATIONS DEVICE CASE**

(71) Applicant: **Q Holdings LLC**, New York, NY (US)

(72) Inventors: **Przemek Godycki**, Brooklyn, NY (US);
Timothy M. Connnelly, Brooklyn, NY (US)

(73) Assignee: **Q HOLDINGS LLC**, New York, NY (US)

(**) Term: **15 Years**

(21) Appl. No.: **29/581,821**

(22) Filed: **Oct. 21, 2016**

Related U.S. Application Data

(62) Division of application No. 29/498,923, filed on Aug. 8, 2014, now Pat. No. Des. 769,852, which is a division of application No. 29/439,255, filed on Jul. 12, 2012, now Pat. No. Des. 713,395.
